UNITED STATES PATENT OFFICE.

JAMES A. MARSH, OF CLEVELAND, OHIO.

DESIGN FOR THE TOP OF A COOKING-STOVE.

SPECIFICATION forming part of Design No. 16,662, dated April 27, 1886.

Application filed November 16, 1885. Serial No. 183,053. Term of patent 7 years.

To all whom it may concern:

Be it known that I, JAMES A. MARSH, of Cleveland, in the county of Cuyahoga and State of Ohio, a citizen of the United States, 5 and a resident of the above-named place, have invented and produced a new and original Design for Tops of Cook-Stoves, of which the following is a specification, reference being had to the accompanying drawing, forming part 10 thereof.

The single figure of the drawing represents a plan view of my design.

Heretofore cooking-stoves of the kind to which my design relates have been made which 15 present, when viewed in plan, three openings—two on the rear of the stove and one intermediate in front.

The leading feature of my design consists in the rectangular face of the top or table of the 20 stove, having two series of circular openings, the openings in each series being within the same parallel lines when drawn longitudinally on the top and diagonally opposite the openings in the opposite series, as shown and described, and particularly pointed out in the 25 claim.

In the drawing, A represents the top or table plate of the stove, formed with an even unbroken surface outside of the openings.

Said plate is provided with two series of openings, represented by *a* and *b*, respectively, the openings in each series being within parallel lines when drawn longitudinally on the plate, and any two of the openings nearest each other in the opposing series falling within 35 corresponding lines when drawn diagonally across the plate, so that the center of the openings in one series comes opposite the center of the space between the openings in the opposite series. 40

What I claim as new, and desire to secure by Letters Patent, is—

The design for a cooking-stove top herein shown and described, the same consisting of a plate, A, rectangular in outline, and provided 45 with two series of openings, *a* *b*, running within parallel lines longitudinally of the plate and within parallel lines diagonally across the plate from both sides, and the openings at the opposite ends of each series being half-way beyond the openings of the opposite series. 50

In testimony whereof I affix my signature, in presence of two witnesses, this the 14th day of November, 1885.

JAMES A. MARSH.
